UNITED STATES PATENT OFFICE.

ASA F. BATCHELDER, OF SCHENECTADY, NEW YORK, ASSIGNEE TO GENERAL ELECTRIC COMPANY, A CORPORATION OF NEW YORK.

ELECTRIC LOCOMOTIVE.

1,008,582.

Specification of Letters Patent. Patented Nov. 14, 1911.

Continuation of application Serial No. 493,093, filed April 30, 1909. This application filed November 7, 1910. Serial No. 590,957.

To all whom it may concern:

Be it known that I, ASA F. BATCHELDER, a citizen of the United States, residing at Schenectady, county of Schenectady, State of New York, have invented certain new and useful Improvements in Electric Locomotives, (being in part a continuation of my application filed April 30, 1909, Serial No. 493,093,) of which the following is a specification.

My invention relates to electric locomotives.

In one aspect, the object of my invention is to provide a new and improved spring or yielding driving connection between a motor armature and a shaft.

In another aspect, the object of my invention is to provide a new and improved system of spring suspension for supporting the motor armature upon an axle or shaft, while at the same time providing for a driving connection between the armature and the axle or shaft.

While I have shown my invention as embodied in a two-truck locomotive, it will, of course, be understood that it may equally well be used in locomotives of other types.

The above mentioned objects of my invention are carried out by means of a yielding driving connection between the armature and the coöperating shaft or axle and the members rigidly mounted on said shaft, which comprises flexible rods extending through said armature and having their ends supported in holes in said members arranged concentric with said shaft or axle.

For a better understanding of my invention, reference may be had to the following description taken in connection with the accompanying drawings, in which—

Figure 1 is a side elevation of the trucks of a two-truck locomotive, a portion of the frame of one truck being broken away and the motor of that truck being shown in cross section; Fig. 2 is a plan of the trucks shown in Fig. 1, the body frame of the cab of the locomotive being shown in outline in dash lines; Fig. 3 is an end elevation of one end of one of the trucks shown in Figs. 1 and 2; Fig. 4 is an elevation, partly in section, showing a pair of wheels and their axle and my improved means for supporting the motor armature yielding upon said axle; Fig. 5 is a fragmentary cross-sectional view 55 of a portion of the spring supporting means for the motor armature illustrated in Fig. 4; and Fig. 6 is a modification showing a pair of wheels and their shaft and my improved yielding driving connection between the motor armature and said shaft.

Referring particularly to Figs. 1 and 2, the trucks A and B are shown as each provided with two pairs of wheels, the axles or shafts of which are mounted for limited vertical movement in truck frames 11 and 12 of similar design. The journal boxes for these axles and the manner in which they are mounted in the truck frames need not be described here since they may be of any well known style and form no part of my invention. Each truck frame is supported upon the journal boxes of its axles by spring systems of suspension fully described and claimed in my application Serial No. 590956, filed Nov. 7, 1910. The trucks are connected by a leading connector 13 of any suitable and well-known form, this connection serving as a hinged joint between the trucks through which the tractive effort of one truck is transmitted to the other, it being understood that in the particular locomotive shown the draw bars are mounted upon the truck frames. The truck A is connected to the body frame of the cab by a pivotal connection 14, of any well-known form, and the truck B is connected to the body frame by a pivotal and longitudinally sliding connection 15, also of any well-known form. The trucks A and B are provided, respectively, with motors 18 and 19 arranged in co-operative relation to the axles of said trucks which are nearest one another, or in other words, nearest the middle of the locomotive. These motors are shown as of the bipolar type in which the armature surrounds the wheel axle, the field structure of each motor being built into and forming a part of the truck frame. The manner in which the armatures of these motors are supported around the wheel axle will be hereinafter fully described. The wheel axles of each truck are geared together by crank pins and connecting rod connections, as clearly shown in Figs. 1 and 2, the crank pins being shown at 21 and the connecting rods at 22. The cranks on each wheel axle at opposite sides of the truck are, of course, set at right angles in order that the connecting rods on both sides of the truck may never be upon dead center at the same time. The frame of the

truck A is supported upon its four journal boxes by springs 25, links 26 and equalizing levers 27 duplicated on both sides of the truck and arranged as shown in the drawing. The frame of the truck B is supported upon its journal boxes through springs 35, links 36 and one equalizing lever 37 arranged as shown. This system of suspension for the motor frames is described and 10 claimed in a divisional application.

I will now proceed to describe the yielding driving connections between the armatures of the motors and the shafts or axles.

Owing to the fact that the torque of single-phase motors is not steady but is constantly varying from zero to the maximum, it has been found desirable, where such motors are used for railway work, to provide a spring drive between the motors and their 15 coöperating shafts whereby this varying torque is reduced to a more or less constant torque. My yielding driving connection may be used for this purpose or for a yielding support and driving connection. In Fig. 25 6, I have shown it merely for a driving connection, while in the other figures of the drawings I have shown it also as a spring support. Although I have shown my yielding driving connection in connection with 30 a shaft having two driving wheels, it may be used in connection with a shaft having two members adapted to coöperate with said connection such as cranks or the like rigidly mounted thereon.

Referring to Figs. 1 to 5, inclusive, each of the armatures of the motors, which may be of the usual form for gearless railway motors, is built upon a hub or spider. The armature is shown in dotted lines at 40 in 40 Fig. 4. This spider is provided with a plurality of circularly arranged holes, through which spring rods 41 are adapted to pass. These rods may be of the form shown in Figs. 4 and 5; that is, they may be larger at 45 their middle portion than at their ends. The ends of the rods 41 are supported in holes in the hubs of the driving wheels, these holes, in the particular construction shown, being lined with a bushing 42 of 50 suitable material, such as brass. By forming the ends of the rods 41, as shown, with a head 43 having a round surface which snugly fits the holes in the bushing 42 and by making the cylindrical portion 44 55 slightly smaller than the hole in the bushing 42, bending of the rod 41 is provided for, and when the portion 44 is brought into engagement with the bushing 42 the effective length of the flexible rods between 60 the supporting points is decreased. With such an arrangement the yielding effect of the rods is decreased after the same have been flexed a certain amount. The assembling of the wheel axle, wheels, motor armature and spring rods 41 is facilitated by

the holes 45 through the crank disks upon these axles, said holes being located in line with the holes through the wheel hubs and, therefore, permitting the rods 41 to be inserted through the crank disks and wheels 70 into the holes in the spider of the motor armature. The bushings 42 may be firmly held in place by spring washers 46 inserted in grooves near the outer end of the holes through the wheel hubs.

Referring to Fig. 6, it will be noted that the arrangement of the spring rods 41 in the armature of the motor and in the wheels is like that of Fig. 4. The armature, which is shown in dotted lines at 40', is, however, 80 journaled about the axle or shaft so that it may move slightly around said shaft. In this arrangement, the armature is supported on the shaft but is yieldingly connected thereto through the rods 41 and the wheels, 85 which are rigidly mounted on said shaft.

Features of my invention shown and described, but not claimed herein, are claimed in my applications, Serial No. 493,093, filed April 30, 1909 and Serial No. 590,956, filed 90 Nov. 7, 1910.

What I claim as new and desire to secure by Letters Patent of the United States, is,—

1. In combination, a shaft, a pair of members rigidly mounted on said shaft and having holes concentric with said shaft, a motor for driving said members having an armature surrounding said shaft, and a yielding driving connection between said armature and said members and shaft comprising 95 flexible rods extending through said armature and having their ends supported in said holes.

2. In combination, a shaft, a pair of members rigidly mounted on said shaft and having holes circularly arranged therein, a motor for driving said members having an armature surrounding said shaft, and a yielding driving connection between said armature and said members and shaft comprising 105 flexible rods extending through said armature and arranged substantially parallel to said shaft and in a circle concentric therewith, the ends of said rods being held in said holes.

3. In an electric vehicle, an axle, a pair of driving wheels rigidly mounted on said axle, a frame in which said axle is journaled, a motor for driving said wheels comprising a field structure mounted on said frame, an armature surrounding said axle, and a yielding support and driving connection between said armature and said wheels and axle comprising flexible rods extending through said armature and having their 110 ends supported in holes in said wheels concentric with said axle.

4. In an electric vehicle, an axle, a pair of driving wheels rigidly mounted on said axle, a frame in which said axle is jour-

naled, a motor for driving said wheels comprising a field structure mounted on said frame, an armature surrounding said axle, and means for yieldingly supporting said armature and driving said wheels therefrom comprising flexible rods extending through said armature and having their ends mounted in holes circularly arranged in the hubs of said wheels.

5. In an electric vehicle, an axle, a pair of driving wheels rigidly mounted on said axle, a frame in which said axle is journaled, a motor for driving said wheels comprising a field structure mounted on said frame, an armature surrounding said axle, and means for yieldingly supporting said

armature for driving said wheels therefrom comprising flexible rods extending through holes in said armature and arranged substantially parallel to said axle and in a circle concentric therewith, the ends of said rods being held in circularly arranged holes in said wheels, said holes being so arranged that the effective length of said flexible rods between the supporting points decreases 25 when said rods are flexed.

In witness whereof, I have hereunto set my hand this 4th day of November, 1910.

ASA F. BACHELDER.
